UNITED STATES PATENT OFFICE.

RICHARD M. HOPKINS, OF YONKERS, NEW YORK, ASSIGNOR TO AMERICAN DISTRICT TELEGRAPH COMPANY, OF NEW YORK, N. Y., A CORPORATION OF NEW JERSEY.

TRANSMITTER.

No. 907,600.

Specification of Letters Patent. Patented Dec. 22, 1908.

Application filed May 11, 1908. Serial No. 432,208.

To all whom it may concern:

Be it known that I, RICHARD M. HOPKINS, a citizen of the United States, residing at Yonkers, in the county of Westchester and State of New York, have invented certain new and useful Improvements in Transmitters; and I do hereby declare the following to be a full, clear, and exact description of the same, such as will enable others skilled in the art to which it appertains to make and use the same.

My invention relates to transmitters, such as are adapted for repeating fire alarm signals and the like, and comprises means whereby, at will, any one of a large number of different signals may be transmitted.

The invention comprises means for adjusting the apparatus, quickly, to send the signal desired.

20 The objects of my invention are, to provide a simple transmitter, whereby any one of a large number of signals may be transmitted without using a plurality of detached signal wheels, one for each different signal, 25 such as it has been the common practice to use heretofore, and to make the transmitter easy to adjust and operate, compact, and relatively inexpensive.

I will now proceed to describe my invention with reference to the accompanying drawings, in which one embodiment of my invention is illustrated, and will then point out the novel features in claims.

In the said drawings: Figure 1 shows a 35 front view of the transmitter; Fig. 2 a side view and partial section thereof; Fig. 3 a transverse section on line $x-x$ of Fig. 2; Fig. 4 shows an elevation of the indicating sector corresponding to the notched break 40 wheel; Fig. 5 shows a perspective elevation of one of the first two adjusting arms, showing particularly the indicator carried thereby; Fig. 6 shows a front view of the last adjusting arm and of the blank arc-shaped 45 strip or sector with which said arm is provided; and Fig. 7 is a detail view of the stop mechanism.

In the drawings, 1 designates a toothed or notched break wheel, mounted upon a shaft 50 2, and arranged to be rotated in the direction of the arrow shown in Fig. 1, by means hereinafter described. A contact spring 3 is arranged to ride over the teeth of this wheel

1 as it revolves, and another contact spring 4 is arranged to make contact with this spring 3 except at such times as spring 3 drops into a notch between two teeth of the wheel. It will be obvious that as the wheel revolves, contact will be made and broken alternately between these springs 3 and 4. 55

In proximity to wheel 1 there is a star wheel 5, arranged to be rotated step by step by engagement with its arms of two pins, 6 and 7, the former carried by the wheel itself, the latter carried by the last of three adjusting arms, 8, 9 and 10. This star wheel is arranged to rotate a disk comprising opposed conductive segments, 11 and 12, electrically connected to each other, and opposed insulating segments, 13 and 14; and brushes, 15 and 16, bear against the periphery of this disk. These two brushes are connected electrically across the contact springs 3 and 4, and it will be seen that when brushes 15 and 16 are connected electrically through conductive segments 11 and 12, a shunt connection is established across brushes or springs 3 and 4, which nullifies the electrical effect of 60 these springs. 65

Wheel 1 has in it a slot 17, through which 70 rows of numbers on certain indicating segments may be seen. The rearmost of these segments, 18 (Fig. 4) is keyed to shaft 2, as is wheel 1, and corresponds in all respects to wheel 1; that is to say, is functionally a part 75 of said wheel, though somewhat in rear thereof, so that between said wheel and segment other segments carried by arms 8, 9 and 10, may move, so as to blanket more or less of the circular row of numbers, 1 to 9 inclusive, which segment 18 carries in position to be seen through slot 17. The first adjusting arm, 8, carries a segment 19, located just in front of segment 18, and likewise is provided with numerals, 1 to 9 inclusive, these numerals being likewise in position to be seen through the slot 17. Segment 19 projects to the right of arm 8. 80

The second adjusting arm, 9, has a similar segment, 20, likewise carrying numerals 1 to 9 inclusive; and the third arm, 10, has a similar segment, 21, which, however, (when the signal is not to include more than three numbers) is not provided with numerals on its surface, this segment 21 being merely a blanketing segment. 90 95 100 105

The spacing of the numerals on segments 18, 19 and 20 corresponds to the spacing of the teeth of wheel 1. Each arm, 8, 9, and 10, has in it an orifice, registering with slot 17, through which a numeral on the segment beneath may be seen. It will be seen that, according to the adjustment of arms 8, 9 and 10, an observer will see, through slot 17 and the orifices in arms 8, 9 and 10, one or more of the numerals on segment 18, followed by one or more numerals on segment 19 (provided arm 9 is not directly against arm 8), followed in turn by one or more numerals on segment 20 (provided arm 10 is not directly 15 against arm 9); the segment 21 hiding the numerals on segment 20 beyond that seen through the orifice of arm 10. The numbers thus seen through the orifices of arms 8, 9 and 10 (3—4—5, according to the particular adjustment of said arms shown in the drawings) constitutes the signal for which the transmitter is set.

Each arm, 8, 9 and 10, carries a filling-piece, 22, mounted on a spring-retracted sliding handle 23 arranged to slide in suitable bearings carried by the arm; such filling piece adapted to fill the notch between any two teeth of wheel 1 and so to prevent spring 3 from dropping so as to break contact with 30 spring 4.

For rotating shaft 2 I have illustrated a simple form of spring motor comprising a spiral spring 24 anchored at one end to a bar 25 of the frame of the machine, the other end 35 of said spring being secured to a shaft 26 on which is mounted a pinion 27 intermeshing with a gear segment 28 carried by a pivoted operating handle 29. A ratchet wheel 30 secured to shaft 26 is adapted to engage a 40 spring-pressed pawl 31 carried by a gear 32 mounted loosely on shaft 26 and intermeshing with a pinion 33 on shaft 2. It will be seen that when arm or handle 29 is rotated to the right until arrested by a stop pin 34 and 45 then released, wheel 1 will be rotated one revolution. A pendulum escapement 35 regulates the rate of movement of the wheel. At the conclusion of one revolution wheel 1 is arrested by reengagement of a pin 36 carried 50 by shaft 2 with a stop arm 37 carried by gear segment 28 (Fig. 7) said stop arm being moved out of the path of the pin 36 when handle 29 is operated to wind the spring.

Wheel 1 will ordinarily be provided with a 55 blank space 38 at that portion of its periphery against which spring 3 rests when the wheel 1 is at rest; and between said blank portion and the main toothed portion of the wheel there may be a toothed portion 39 containing 60 a few teeth, which will send in a preliminary signal such as the "class" signal required in some localities. In connection with this toothed portion 39 there may be an adjustable segment 40, which, when set out to the 65 periphery of wheel 1, prevents spring 3 from

dropping into the notches 39. This segment 40 is shown in such position in Fig. 1. When the segment is moved inward it permits the preliminary signal to be sent.

The operation of the apparatus is as follows: To send a number of three figures or less, the operator adjusts the arms 8, 9 and 10, by raising the handles 23 and moving the arms as required until the desired numbers are seen through the orifices in said arms, then 70 releasing said handles, whereupon the filling blocks, 22, will drop into the corresponding notches of wheel 1, holding the arms 8, 9 and 10 in the positions to which they have been adjusted, and at the same time preventing the spring 3 from dropping into such notches. The handle 29 is then pulled to the right, winding up spring 24, and is released, whereupon wheel 1 begins to rotate. As 75 spring 3 passes over the notches 39 contact is broken and remade between springs 3 and 4, (provided segment 40 has been moved inward), thus sending a preliminary signal. When spring 3 passes over the notches of the main notched portion of wheel 1 the main 80 signal is transmitted. The filling pieces 22 prevent the spring 3 from dropping where these filling pieces are, so producing the slight pause between numerals of the same signal necessary to distinguish the strokes of 85 one number from those of the next. When the filling piece 22 of arm 10 passes spring 3 the pin 7 actuates star wheel 5, reversing the 90 position of the disk carried thereby, so that conductive segments 11 and 12 are now in contact with brushes 15 and 16, so completing 95 a shunt connection across springs 3 and 4, so that further breaking of contact at these springs has no effect on the signal circuit. When wheel 1 returns to normal position pin 100 6 actuates the star wheel again, breaking the connection between brushes 15 and 16. The 105 transmitter is then ready for adjustment to send another signal.

It will be apparent that by setting arm 8 110 to a desired number, and by placing arms 9 and 10 with their filling pieces 22 in notches adjacent to that of the filling piece of arm 8, a signal of only one number may be sent; and similarly that by proper adjustment of the 115 arms signals of only two numbers may be sent. The instrument may of course have as many arms as desired.

What I claim is:—

1. A transmitter comprising in combination a notched disk, a contact device adapted to be operated by passage over the notches of said disk, one of said members adapted for complete rotation with respect to the other, means for rotating the one with 120 respect to the other, and one or more adjustable pieces adapted to close one or more of said notches to prevent operation of said contact device and means preventing operation of a circuit by said contact device dur- 125 130

ing passage thereof over notches of said disk, after passage over a predetermined number of said notches.

2. A transmitter comprising in combination a notched disk, a contact device adapted to be operated by passage over the notches of said disk, one of said members adapted for complete rotation with respect to the other, means for rotating the one with respect to the other, one or more adjustable filling pieces adapted to fill one or more of said notches to prevent operation of said contact device, and means preventing operation of a circuit by said contact device, during passage over the notches of said disk, after the passage of a predetermined number of said notches.

3. A transmitter comprising in combination a notched disk, a contact device adapted to be operated by passage over the notches of said disk, one of said members adapted for complete rotation with respect to the other, means for rotating the one with respect to the other, one or more adjustable pieces adapted to close one or more of said notches to prevent operation of said contact device, and contact means operated by the rotatable member after passage of said contact device over a predetermined number of said notches arranged to prevent operation of a circuit by said contact device.

4. A transmitter comprising in combination a notched disk, a contact device adapted to be operated by passage over the notches of said disk, one of said members adapted for complete rotation with respect to the other, means for rotating the one with respect to the other, one or more adjustable pieces adapted to close one or more of said notches to prevent operation of said contact device, and shunt circuit contact means operated by the rotatable member after passage of said contact device over a predetermined number of said notches arranged to close a shunt connection across said first named contact device.

5. A transmitter comprising in combination a notched disk, a contact device adapted to be operated by passage over the notches of said disk, means for rotating the one with respect to the other, one or more adjustable pieces adapted to enter and close one or more of said notches to prevent operation of said contact device, and a carrying arm for each such piece having a sliding connection therewith, said adjustable piece when in place in one of said notches being held in place thereby and serving also to lock the corresponding segment.

6. A transmitter comprising in combination a notched disk, a contact device adapted to be operated by passage over the notches of said disk, means for rotating the one with respect to the other, one or more adjustable pieces adapted to close one or

more of said notches to prevent operation of said contact device, a carrying arm for each such piece having a sliding connection therewith, and a spring tending to hold each such piece in the notch in which it is placed.

7. A transmitter comprising in combination a notched disk, a contact device adapted to be operated by passage over the notches of said disk, means for rotating the one with respect to the other, said disk having in it a slot and having in rear of said slot a numbered segment, an adjustable piece adapted to close one of said notches to prevent operation of said contact device, and a segment between said disk and the numbered segment thereof, adjustable with said piece and adapted to hide more or less of the numbers on the said disk segment.

8. A transmitter comprising in combination a notched disk, a contact device adapted to be operated by passage over the notches of said disk, means for rotating the one with respect to the other, said disk having in it a slot and having in rear of said slot a numbered segment, two or more adjustable pieces adapted to close two or more of said notches to prevent operation of said contact device, and over-lapping segments movable with said pieces and adapted to hide more or less of the numbers of said disk segment, each of said over-lapping segments except the last having corresponding numbers adapted to be hidden, more or less, by the rest of said segments.

9. A transmitter comprising in combination a notched disk, a contact device adapted to be operated by passage over the notches of said disk, means for rotating the one with respect to the other, one or more adjustable pieces adapted to close one or more of said notches to prevent operation of said contact device, a star wheel and means operated thereby preventing operation of a circuit by said contact device after the passage of a predetermined number of said notches, a pin carried by said disk for operating said star wheel and another pin adjustable with the last of said adjustable pieces and likewise adapted to operate said star wheel.

10. A transmitter comprising in combination a notched disk, a contact device adapted to be operated by passage over the notches of said disk, means for rotating the one with respect to the other, a plurality of adjustable pieces adapted to close notches of said disk to prevent operation of said contact device, swinging arms carrying said adjustable pieces, a star wheel and contact means operated thereby preventing operation of the circuit by said contact device after the passage of a predetermined number of said notches, a pin carried by said disk for operating said star wheel and another pin carried by the last of said arms and likewise adapted to operate said star wheel.

11. A transmitter comprising in combination a notched disk, a contact device adapted to be operated by passage of the notches of said disk, means for rotating the one with respect to the other, an adjustable piece adapted to close one or another of said notches to prevent operation of said contact device, a star wheel and contact means operated thereby for closing a shunt connection across said first named contact device, and means for operating said star wheel to

reverse such shunt contact device after the passage of said first named contact device over said adjustable piece and also when the disk nears its normal position.

In testimony whereof I have signed this specification in the presence of two subscribing witnesses.

RICHARD M. HOPKINS.
